UNITED STATES PATENT OFFICE.

ROLANDIS A. BLAIR, OF FORT WAYNE, INDIANA, ASSIGNOR TO THE P & M COMPANY, OF CHICAGO, ILLINOIS. A CORPORATION OF ILLINOIS.

RAIL ANCHOR.

Original application filed September 8, 1920, Serial No. 408,799. Divided and this application filed March 17, 1922. Serial No. 544,493.

To all whom it may concern:

Be it known that I, ROLANDIS A. BLAIR, a citizen of the United States, residing at Fort Wayne, in the county of Allen and State of Indiana, have invented certain new and useful Improvements in Rail Anchors, of which the following is a specification.

My invention relates to devices known as rail anchors or anti-creepers, to prevent the longitudinal creep of railroad rails, and has for its primary object to provide an improved device of this character which will be light in weight, inexpensive to manufacture, possesses sufficient rigidity to withstand the stresses to which devices of this character are subjected when in service, which will take a firm hold on the rail, and which will be sufficiently resilient to prevent its hold on the rail being loosened by vibration or other causes having that tendency.

It is well known that railroad rails, even when made in conformity with the same standard, often vary in width and thickness of their base flanges. This imperfection may be due to the wearing away of the bearing surfaces of the rolls employed in manufacturing the rails, or it may be due to the corrosion of the rails after they have been in service for some time. Such conditions as these present certain disadvantages in connection with one-piece devices, as ordinarily these devices are not well adapted to be used on rails which vary in the width and thickness of their base flanges.

It is one of the specific objects of my invention to provide a new and improved rail anchor, preferably a one-piece device, which can be used effectively on rails, the base flanges of which may vary in width or thickness. A further specific object is to provide a rail anchor which will check or counteract the various tendencies, such as vibration, counter-creeping, and the like, which operate to cause rail anchors to work loose on the rail. In this connection my invention contemplates the provision of a rail anchor made preferably of spring metal which is stressed transversely of the rail base when in its applied position and hav-

ing the jaw portions so disposed with relation to a portion of the device adapted to bear against a tie or other stationary part of the road-bed that any longitudinal movement of the rail toward the tie or other abutment will further tension the anchor and thereby increase its grip on opposite edges of the rail base. 55

A further object is to provide a rail anchor of novel construction which will be effective against movements or creeping of the rail in either direction. 60

A further object is to provide a device which may be conveniently and quickly applied to or removed from a rail, when desired. 65

My invention consists in the new and improved constructions to be hereinafter described and claimed for carrying out the above stated objects and such other incidental objects as will appear from the following description of a preferred embodiment of the invention as illustrated in the accompanying drawing, in which,— 70

Fig. 1 is a view in perspective of a railroad rail showing my improved anchor device applied thereto in its operative position. 75

Fig. 2 is a plan view of the structure shown in Fig. 1 with the addition of a cross tie providing an abutment for the anchor device. 80

Fig. 3 is a view in perspective of the anchor device before the same is applied to a rail, and

Fig. 4 is a side elevation of the anchor illustrating the manner in which it is applied to a rail. 85

Like characters of reference designate like parts in the several figures of the drawing. 90

Referring to the drawing 10 designates a railroad rail and 11 one of the cross ties on which the rail is supported.

The rail anchor preferably consists of a single piece of metal cut and bent to the form shown in Fig. 3. I preferably use a flat piece of spring metal. The device is formed so as to provide hook or jaw portions 12—12 at one end adapted to engage with one of the base flanges of the rail. 95 100

The other end of the device is provided with hook or jaw portions 13 and 14 which are adapted to engage with the other edge of the rail base. The web portions 15 and 16 of the anchor intervening between the jaws 12-12 and the jaws 13 and 14, respectively, are narrower than the ends of the anchor so that they will extend under the base of the rail. In order to prevent any rocking movement of the anchor on the rail I preferably provide the two jaws 12, one on each side, although it will be obvious from the following description that the anchor will take a very reliable hold on the rail if only one such jaw is provided. The free end of the web portion 16 is formed with an extension 17 to provide a locking tongue adapted to bear against the side of the jaw portion 13. The web portions 15 and 16 of the anchor are curved so that the distance between the jaws 12 and 13 and 12 and 14, when the anchor is free of the rail, is normally less than the transverse distance across the rail base, thereby making it necessary to stress the curved webs of the anchor in applying the device to a rail. The free ends of the web portions 15 and 16 are spread apart and the tongue 17 is bent around into engagement with the jaw portion 13, preferably before the anchor is applied to the rail. The jaws 12-12 are formed with beveled surfaces to facilitate the application of the anchor to the rail and the tongues 17 and jaw portion 13 are preferably, though not necessarily, formed with beveled surfaces 19 and 20, respectively, to facilitate entry of the tongue into engagement with the jaw portion 13.

The anchor is applied to the rail as follows: it is placed under the rail with the jaws 13 and 14 engaging the edge of one of the base flanges of the rail as indicated in dotted lines in Fig. 4. A track bar 21 is inserted between the inner surface of the jaw end 12 of the anchor and the edge of the adjacent base flange and is manipulated to elongate the anchor sufficiently to permit the beveled surfaces 18-18 of the jaws 12-12 to ride over and to snap into engagement with the edge of the rail base, as shown in full lines in Fig. 4. This operation eliminates substantially all curvature from the web portions 15 and 16 and ordinarily the jaws of the anchor will have a tight binding grip on the rail base. The locking tongue 17 is adjustable and if there should be any looseness in the engagement of the anchor with the rail base after being applied as aforesaid or if any such looseness should develop, as by corrosion, it may be eliminated by bending the tongue inwardly toward the rail thereby forcing the jaws 13 and 14 further apart and augmenting the hold or grip of the jaws on the rail base.

In an anchor device of this general construction the jaw portion 13 and locking tongue 17 may be relatively long and the tongue bent to such initial angular position that its range of adjustment makes it practical to apply the anchor to rail bases of varying widths and contour. The forcing apart of the jaws 13 and 14 subjects the webs 15 and 16 to further stress tending to straighten the curved portions thereof and forces the vertical walls of the jaw portions into tight gripping engagement with the vertical edges on opposite sides of the rail base; consequently the jaws need not necessarily grip both top and bottom surfaces of the rail base and therefore may be made slightly loose fitting in this respect, thereby accommodating rail bases of different thickness or having upper surfaces of different slope.

The anchor, as above described, will hold the rail against creeping forwardly, that is to say in a direction from the anchor toward the tie against which the anchor bears and the hold which it takes upon the rail base is maintained, as against vibration or other disturbing influences because the anchor is under strain when it is in its operative position on the rail. Furthermore, the anchor will hold the rail against creeping in the opposite direction when the anchor itself is held by a ballast or a tie.

This application is a division of my co-pending application Serial No. 408,799, filed September 8, 1920.

I claim:

1. A rail anchor provided at one end with means for engaging one side of a rail base and at the other end with means for engaging the other side of said rail base at spaced points and which are adapted to be forced apart to increase the grip of the anchor on the rail, said means for engaging opposite sides of the rail base being so disposed that the distance between them is normally less than the widths of the rail base when the anchor is free of the rail, and a portion of the anchor being resilient whereby said means for engaging opposite sides of the rail base may be forced apart in applying the anchor to the rail.

2. A rail anchor provided at one end with a jaw for engaging one side of a rail base and at the other end with a pair of jaws having a spaced relation to each other for engaging the other side of said rail base, the jaws of said pair of jaws being adapted to be forced apart to increase the grip of the anchor on the rail, a portion of the anchor being resilient whereby said pairs of jaws for engaging opposite sides of the rail base may be forced apart in applying the anchor to the rail.

3. A rail anchor formed at each end with a pair of spaced jaws for engaging opposite

- sides of a rail base, the jaws of one pair being adapted to be forced apart when the anchor is applied to the rail, the portion of the anchor between said jaws being resilient and the pairs of jaws being arranged so that the distance between them is normally less than the width of the rail base whereby the anchor is elongated during its application to the rail.
10. 4. A rail anchor formed at each end with a pair of spaced jaws for engaging opposite sides of a rail base, the portion of the anchor between said pairs of jaws being resilient and the pairs of jaws being arranged so that the distance between them is normally less than the width of the rail base whereby the anchor may be stressed in the direction of its length during its application to the rail, said anchor being provided with means for forcing apart the jaws of one pair.
15. 5. A rail anchor formed at each end with a pair of jaws for engaging opposite sides of a rail base, the portion of the anchor intervening between said pairs of jaws being bent so that the distance between said pairs of jaws is less than the width of the rail base, and said bent portion being adapted to be straightened so as to elongate the anchor in applying it to a rail, said anchor being provided with means for forcing apart the jaws of one pair.
20. 6. A rail anchor comprising a yoke member formed at one end with means for engaging one side of a rail base and at the other end with separate means spaced with relation to each other for engaging the other side of said rail base, and locking means for maintaining said last engaging means in said spaced relation; a portion of the yoke intervening between said rail engaging means being resilient and adapted to be elongated transversely of the rail when the yoke is in its applied position.
25. 7. A rail anchor comprising a yoke member formed at one end with means for engaging one side of a rail base and at the other end with separate means spaced with relation to each other for engaging the other side of said rail base, and locking means for maintaining said last engaging means in said spaced relation; a portion of the yoke intervening between said rail engaging means being bent and the yoke being adapted to be applied to the rail by straightening said bent portion.
30. 8. A rail anchor comprising a yoke member formed at one end with means for engaging one side of a rail base and at the other end with separate means spaced with relation to each other for engaging the other side of said rail base, and locking means for maintaining said last engaging means in said spaced relation; a portion of the yoke intervening between said rail engaging means in said spaced relation; a portion of the yoke intervening between said rail engaging means being bent and the yoke being bent and the yoke being adapted to be applied to the rail by straightening said bent portion.
35. 9. A rail anchor provided at one end with means for engaging one side of a rail base and at the other with jaws having a spaced relation to each other for engaging the other side of said rail base, the portion of the anchor intervening between said means and jaws being resilient whereby said means and jaws are adapted to be forced apart when applied to a rail, and a locking tongue positioned between said jaws to maintain them in spaced relation.
40. 10. A rail anchor provided at one end with means for engaging one side of a rail base and at the other with jaws having a spaced relation to each other for engaging the other side of said rail base, the portion of the anchor intervening between said means and jaws being resilient whereby said means and jaws are adapted to be forced apart when the anchor is applied to a rail, and a locking tongue positioned between said jaws to maintain them in spaced relation.
45. 11. A rail anchor provided at one end with means for engaging one side of a rail base and at the other with jaws having a spaced relation to each other for engaging the other side of said rail base, the portion of the anchor intervening between said means and jaws being bent so as to permit said means and jaws to be forced apart when the anchor is applied to a rail and a locking tongue positioned between said jaws to maintain them in spaced relation.
50. 12. A rail anchor provided at one end with means for engaging one side of a rail base, and at the other with jaws having a spaced relation with each other for engaging the other side of the rail base and formed intermediate said means and jaws with a bent portion adapted to be straightened when applying the anchor to a rail, and a locking tongue positioned between said jaws to maintain them in spaced relation and adapted to be adjusted to force said jaws further apart.
55. 13. A rail anchor provided at one end with means for engaging one side of a rail base, and at the other with jaws having a spaced relation with each other for engaging the other side of the rail base and formed intermediate said means and jaws with a bent portion adapted to be straightened when applying the anchor to a rail, and a locking tongue positioned between said jaws to maintain them in spaced relation and

adapted to be adjusted to force said jaws further apart, and further straighten said bent portions.

14. A rail anchor provided at one end with means for engaging one side of a rail base and at the other with jaws having a spaced relation with each other for engaging the other side of the rail base and formed intermediate said means and jaws with a bent portion adapted to be straightened when applying the anchor to a rail, a tie abutting portion disposed at the said jaw end of the anchor, and a locking tongue positioned between said jaws to maintain them in spaced relation and adapted to be adjusted to force said jaws further apart and further straighten said bent portion.

15. A rail anchor comprising a pair of bars adapted to extend under the base of a rail and connected together at one end, one of said bars at that end having means for engaging one side of the rail base, each bar at the other end having a jaw for engaging the other side of the rail base and said bars being formed intermediate their ends with curved portions adapted to be straightened by stressing the anchor in applying it to the rail, and a locking means adapted to be bent to force the free ends of said bars apart, whereby the grip of the anchor on the rail is increased.

16. A rail anchor comprising a pair of bars adapted to extend under the base of a rail and connected together at one end, one of said bars at that end having means for engaging one side of the rail base, each bar at the other end having a jaw for engaging the other side of the rail base, and being formed intermediate its ends with a curved portion adapted to be straightened by stressing the anchor in applying it to the rail, and a tongue associated with one of said bars adapted to be bent to force the free ends of said bars apart, whereby said intermediate curved portions are subjected to further stress and the grip of the anchor on the rail is increased.

17. A rail anchor comprising a pair of bars adapted to extend under the base of a rail and connected together at one end, one of said bars at that end having means for engaging one side of the rail base, each bar at the other end having a jaw for engaging the other side of the rail base and being formed intermediate its ends with a curved portion adapted to be straightened by stressing the anchor in applying it to the rail, and a tongue associated with one of said bars adapted to be bent to various adjusted positions to force the free ends of said bars apart, whereby said intermediate curved portions are subjected to further stress and the grip of the anchor on the rail is increased.

18. A one-piece rail anchor comprising a metal member bent to the shape of a V, means

at the apex of said member to engage one side of a rail base and means at the other end of each leg of said V to engage the other side of the rail base, each of said legs being formed intermediate its free ends and said apex with a curved portion adapted to be stressed in applying the anchor to a rail, and an adjustable locking tongue on one of said legs adapted to bear against the other leg to force said legs apart and subject said intermediate curved portions to further stress and increase the grip of the anchor on the rail.

19. A rail anchor comprising a pair of bars adapted to extend under the base of a rail and connected together at one end, one of said bars at that end having a jaw for engaging one side of the rail base, each bar at the other end having means for engaging the other side of the rail base, locking means for maintaining the free ends of said bars in spaced relation, said jaw having a beveled surface adapted to ride over the rail base when the anchor is applied to the rail, said locking means being adjustable whereby the grip of said jaw and rail engaging means on the rail base may be increased.

20. A resilient one piece rail anchor comprising a metal member bent in the shape of a V, each leg of which is slightly curved and provided with means to engage opposite sides of the rail base, and an extension on one of said legs adapted to maintain the free ends of said legs in spaced relation, said anchor being applied to the rail base by straightening said legs, said extension being adjustable whereby the grip of said rail engaging means may be increased.

21. A resilient rail anchor comprising bars to extend under the base of a rail from edge to edge thereof and members intervening between said bars at opposite ends of the anchor, said anchor provided at its opposite ends with rail engaging means normally a shorter distance apart than the width of the rail and the anchor being formed so as to be capable of elongation in application to the rail.

22. A resilient rail anchor comprising bars to extend under the base of a rail from edge to edge thereof, and members intervening between said bars at opposite ends of the anchor, said anchor provided at opposite ends with rail engaging means normally a shorter distance apart than the width of the rail and said bars being curved and adapted to be straightened out to elongate the device in application to the rail.

23. A resilient rail anchor comprising bars to extend under the base of a rail from edge to edge thereof, and members intervening between said bars at opposite ends of the anchor, said anchor provided at opposite ends with pairs of rail engaging jaws normally a shorter distance apart than the

width of the rail and the anchor being formed so as to be capable of elongation in application to the rail.

24. A resilient rail anchor comprising bars to extend under the base of a rail from edge to edge thereof, and members intervening between said bars at opposite ends of the anchor, said anchor provided at opposite

ends with pairs of rail engaging jaws normally a shorter distance apart than the width of the rail and the anchor being formed so as to be capable of elongation in application to the rail and capable of being strained so as to increase the distance between the jaws of one pair of jaws.

ROLANDIS A. BLAIR.
